United States Patent Office

Des. 184,540
Patented Mar. 3, 1959

184,540

HARD SURFACE FLOOR COVERING OR SIMILAR ARTICLE

Harry A. Shortway, Glen Rock, N. J., assignor to Con-goleum-Nairn Inc., Kearny, N. J., a corporation of
New York

Application May 14, 1958, Serial No. 50,873

Term of patent 14 years

(Cl. D92—17)

The figure is a plan view of a hard surface floor covering or similar article showing a full repeating unit between the dashed lines thereof.

I claim:

The ornamental design for a hard surface floor covering or similar article, substantially as shown.
